BOX OR CARTON AND BLANK THEREFOR

William H. Weil, Hollis, N. Y., assignor to
Stransky Products Corporation, New York,
N. Y., a corporation of New York

Application October 3, 1936, Serial No. 103,827

2 Claims. (Cl. 206—44)

This invention relates to boxes or cartons and blanks therefor, the box providing means for closely enwrapping and securing therein supports for articles, the blank being preferably adapted to having articles of merchandise positively secured thereto preliminary to setting the blank up into box shape, and being foldable into such shape. The blank with the articles mounted thereon may be stored or shipped flat so as to take up relatively small space as compared with the size of the box when it is set up, the articles in the box being securely contained therein so that they will not shift about, rattle or become detached from the support or supports upon which they are mounted.

These being among the objects of the present invention, the same consists of certain features of construction and combinations of parts to be hereinafter described and then claimed with reference to the accompanying drawing, showing a preferred embodiment of the invention, and in which:

Fig. 1 is a plan of a blank according to the present invention, the broken lines indicating fold lines or folds;

Fig. 2 is a plan view of some of the panels shown in Fig. 1, and illustrating articles of merchandise attached thereto;

Fig. 3 is an elevation of the parts shown in Fig. 2, both figures intended to illustrate a partial folding up of the blank;

Fig. 4 is an end view of parts shown in Figs. 2 and 3 and showing an additional step in folding the blank;

Fig. 5 is a perspective view of broken away end portions of the parts shown folded up in Fig. 4;

Fig. 6 is a perspective view of a box or carton made from a blank according to the present invention, articles of merchandise being indicated in broken lines;

Fig. 7 is a section in solid lines taken on line 7—7, Fig. 10, the articles of merchandise being omitted therefrom for the sake of clearness;

Fig. 8 is a similar section, except that the articles of merchandise are illustrated and certain flaps shown in Fig. 7 are omitted, for the sake of clearness;

Fig. 9 is a section on the line 9—9, Fig. 10, also in solid lines for the sake of clearness; and

Fig. 10 is a longitudinal section through Fig. 6, the lines being solid black and not cross hatched for the sake of clearness.

Referring to Fig. 1, the blank of sheet material there shown may be of cardboard or other similar tough paper material. The illustrated blank com-

prises panels 11, 12, 13, 14, 15, 16, 17, 18, 19, making nine panels in all for the preferred construction of blank. These panels extend longitudinally of the blank, in succession one after the other, and are separated by transverse fold lines 20, 21, 22, 23, 24, 25, 26, 27 adapting the blank to be folded over and over away from one surface thereof, which fold lines may be created by scoring the blank upon the other surface thereof which is shown in Fig. 2, the broken lines in Fig. 1 indicating that the scoring is not on the exposed surface of Fig. 1.

The transverse fold lines of the blank define different breadths of panels longitudinally of the blank, the panels 12, 14, 16 and 18 being of substantially the same breadth, while panels 11, 13 are of substantially the same breadth as each other, panel 15 of rather less breadth than panels 11, 13, and panels 17, 19 of substantially the same breadth, but of less breadth dimensions than that of panel 15.

The opposite ends of the panel 15 are provided with similar flaps 28 which are adapted to fold upon fold lines 29—29 extending longitudinally of the blank. The blank is incised or sheared lengthwise thereof at 30, along lines extending in line with the fold lines 29, the incisions 30 extending to the fold line 24. Such incisions provide the panel 15 with flaps 28 at opposite ends which are of greater breadth than the distance between the fold lines 23, 24 which define the panel 15, thereby providing lateral extensions or shoulders 31 at corresponding portions of the flaps 28. The construction just described is of particular advantage when a box or carton is set up from the blank, and is to contain articles of merchandise supported by parts of the blank.

Preferably the portion of the blank which comprises panels 11, 12, 13 and 14 are provided with flaps 32 defined by fold lines 33 at the end of the panel 13, with extensions 34 defined by fold lines 35 at the ends of panel 12, end portions of which provide flaps 36 defined by fold lines 37, and with flaps 38 defined by fold lines 39 the ends of panel 11. The panels 11, 12, 13 and 14, together with their flaps may be characterized as the wrapper or enclosing portion of the box or carton. Preferably the panel 12 is provided with a window opening 40 for receiving a pane of Cellophane or like transparent material, and panel 14 may also have a window.

The foldable blank is preferably provided with means for affixing articles of merchandise thereto on the panel or panels which lie adjacent to the extensions or shoulders 31 of the flap 28, to which

end a series of tabs 41 may be struck out from the material of the panel 16 and a series of tabs 42 struck out from the material of the panel 18, and these tabs are indicated in Fig. 1 as extending in a direction away from the exposed surface of the blank. To these tabs 41, 42 there may be positively secured and held upon the panels 16, 18 a plurality of articles of merchandise, in the manner disclosed by U. S. Letters Patent to Jacob Strand, No. 1,581,886 for a sales and display card. In that patent the tabs such as 41 or 42 are combined in such way with assembled picture hangers, such as 43, and nails, such as 44, as that the assembled articles of merchandise are prevented from being accidentally detached from their supports. In Fig. 1 the articles of merchandise are not illustrated as they would probably be located upon the unexposed surface of the blank there shown, unless the tabs are on the exposed surface.

In Figs. 2, 3, 4 and 5 some of the steps in folding up the blank to set up or provide a box or carton are shown. In Fig. 2 it is assumed that, with the articles of merchandise attached, the panels 15, 16, 17, 18 and 19 had been folded up into more or less box shape, and these parts go within the ultimate wrapper so as to be contained within the outer walls of the box. The folding together of the panels 16, 17, 18 and 19 disposes the articles of merchandise to view which are upon the panel 18, while the articles on panel 16 as well as such panel, would be beneath panel 18. Fig. 3 clearly shows how the articles of merchandise would look when looking directly at the panel 17, and it is clear that the tabs 41, 42 for supporting the articles will extend in opposite directions respectively from the panels 16 and 18. Figs. 2 and 3 both show the flaps 28 of panel 15 as extended away from the major portion of the blank, as in Fig. 1, but in Fig. 4 the panel 15 has been folded away from panel 16 so as to be disposed opposite to the panel 17, in which case the extensions or shoulders 31 are shown as downward, and the panel 14 is shown as turned at right angles to panel 15 and its flaps 28. Of course the relative arrangement in folding need not be as shown in Fig. 4 and it depends upon the direction in which the workman folds the parts to obtain the relative position shown in Fig. 4.

In Fig. 5 the panels which have been folded or set up as just described are shown in perspective, so that the disposition of the parts at this stage of the folding will be clear. In this figure it will be seen that the panel 14 is at the bottom, while the panels 16 or 18 are in succession above panel 14, and one of the flaps 28 is shown in the position that it then has in line with the panel 15, with its shoulder or extension 31 extending upwardly in such plane, so that the same will be above the plane of the panel 16. In this view it is also seen that the panel 19 extends upwardly from panel 18 so that its edge is disposed in the corner formed by panels 15 and 16. The next step is to turn the flaps 28 in the direction indicated by the arrow in Fig. 5 towards the open ends of the spaces between the panels 16, 18 and 14. The next step is to complete the wrapping and enclosing of the article supporting panels and their concomitant parts by the wrapper which is provided by the panels, etc. shown in Fig. 1 and which are there illustrated as above the panel 15. The ultimate disposition and arrangement of the illustrated parts to complete the box with its contents will be made clear by the description of the figures after Fig. 5.

Referring now to Figs. 6 to 10 inclusive, the same reference numerals are used for parts of the

box corresponding with the parts of the blank shown in Fig. 1, so that it would be easier to identify corresponding parts. In Figs. 6 to 10 inclusive the parts beyond the panel 15 and including the panel 14 have been brought around the ultimate contents of the box so as to constitute a wrapper or enclosing means. In a well known manner the panel 14 constitutes the bottom wall of the box or carton, the panel 12 the top wall of the box and the panels 11, 13, the side walls of the box, the 10 wall 13 being between the walls 12, 14 and the panel 11 being at the opposite side of the box. The flaps 32 and 28 are brought around towards each other so that with the extensions 34 they constitute with the flaps 28 multi-ply walls of the box 15 between the sides, top and bottom, while the flaps 36 are folded towards the box and inserted between the edges of the multi-ply walls and the bottom wall 14. The flaps 28 and 36 extend in the same direction as shown in Fig. 9, while the flaps 32 extend in the opposite direction, the extensions 34 being outside thereof. The disposition of the flaps is also shown in Fig. 10. It will be seen that the articles of merchandise will not only be located in the space between the wall or partition 16 and the top wall 12, but between the wall or partition 18 and the bottom wall 14. The means for locking the box or rather securing the box in box-shape, together with the contents, reside in the extensions 34 and the flaps 36, in this form of the invention.

Attention is directed to the fact that the flaps 28 extending at an angle to the wall 15 as shown more clearly in Figs. 7 and 9 lie against the adjacent edges of the walls between them and furthermore their lateral extensions or shoulder portions 31 extend at substantially right angles to and beyond the intermediate partition wall 16, this being one of the walls which supports the articles of merchandise affixed thereto, and the upper and lower edges of the flaps 28 will lie closely adjacent to or in contact with the walls 12, 14 thereat. As the wall 15 and its flaps 28 as well as the walls 16 and 17 are composed of comparatively stiff cardboard and as the wall 18 and the wall 19 are also of such comparatively stiff material, the partition walls 16, 18, supporting the articles of merchandise will be reliably held and supported by the flaps 28 and their shoulders 31, and the supports for the articles will be reinforced thereby, and as the edges of said flaps and the other flaps lie substantially coincident with each other as shown in Fig. 10 the bottom and top of the box will also be reinforced. This is particularly true because the flaps 28 are preferably integral extensions of the wall 15 and may be folded at substantially right angles thereto in setting up the box. It will furthermore be seen that in this form of the invention the articles of merchandise supported by the partition wall 18 rest upon the bottom wall 14, through the intervention of the flaps 36, and assist in sustaining the position of the parts within the box.

It has been stated that the parts 14, etc. beyond the part 15 shown in Fig. 1 constitute a wrapper for the contents of the box and it is to be understood that the wrapper may be of any other suitable construction than that shown. Obviously the locking or securing means for the box may be provided in any other well known manner, as by providing a slit in the wall 15 and forming the wall 11 with a suitable locking tongue for insertion into said slit, as is common prac-

tice with cartons. In such case it is obvious that the flaps 38 will not be necessary.

It is also obvious that the panels 18, 19 shown in Fig. 1 may be omitted, in which case the lower edge of panel 17 would rest upon the adjacent wall of the box, and there would be but a single series of articles in the box, supported upon the panel 16. In such case the series of articles on panel 16 would be supported by two walls, wall 15 and a broader wall 17 than that shown, and the flaps 28 with the offset portions 31 will provide additional support for the articles which are reliably secured to the panel 16.

Of course other articles than picture hangers 15 and their nails may be similarly mounted in a box and held against relative movements.

It will be obvious to those skilled in the art that further modifications of the invention may be made without departing from the spirit of the 20 invention as defined in the appended claims.

What I claim as new is:

1. A box blank, of somewhat stiff sheet material, comprising at least two panels connected by a fold line and of relatively different breadths 25 transversely of the fold line and of substantially the same lengths, flaps foldably connected with the opposite ends of the smaller panel by fold lines to adapt them to be folded toward such panel, the blank being incised along lines aligned 30 with such flap fold lines and up to the panel connecting fold line for a distance much less than the said breadth of the larger panels, and the incisions defining a greater breadth for the flaps

than the breadth of the smaller panel, the larger panel adapted for supporting articles, and covering means adapted to closely enwrap, surround and secure therein the two panels and the flaps in such position that the panels extend at an angle to each other and the flaps extend at an angle to the panels, the breadth of such flaps being such as to approximately define the distance between the bottom and the top of the covering means.

2. A box or carton, of cardboard-like material including two inner walls foldably connected together, and of relatively different breadths transversely of the line of connection and of substantially the same lengths, the walls lying at an angle to each other, flaps foldably connected with the opposite ends of the smaller wall and being of greater breadth than such wall, to provide lateral extensions, such flaps being folded inwardly against the opposite ends of the two 20 walls to extend at substantially right angles to such walls, with the extensions projecting away from the plane of the larger wall and remaining in the same planes as the flaps, such larger wall adapted for receiving an article, and wrapping 25 means closely enclosing and securing the two walls, with the flaps with their lateral extensions extending along inner surfaces of the wrapper, and opposite edges of the flaps with their extensions confined by opposed portions of the wrapper and defining the distance between such portions.

WILLIAM H. WEIL.
